(57) **CLAIM**

The ornamental design for a hanger for a bird feeder with moat for containing water to restrict access of crawling insects, as shown and described.

DESCRIPTION

FIG. 1 is a perspective view of a hanger for a bird feeder with moat for containing water to restrict access of crawling insects in accordance with a first embodiment of the present invention, wherein a perspective view from the opposite side is substantially a mirror image thereof;

FIG. 2 is a front elevation view of the hanger for a bird feeder of FIG. 1;

FIG. 3 is a rear elevation view of the hanger for a bird feeder of FIG. 1;

FIG. 4 is a left elevation view of the hanger for a bird feeder of FIG. 1;

FIG. 5 is a right elevation view of the hanger for a bird feeder of FIG. 1;

FIG. 6 is a top plan view of the hanger for a bird feeder of FIG. 1;

FIG. 7 is a bottom plan view of the hanger for a bird feeder of FIG. 1;

FIG. 8 is a perspective view of a hanger for a bird feeder with moat for containing water to restrict access of crawling insects in accordance with a second embodiment of the present invention, wherein a perspective view from the opposite side is substantially a mirror image thereof;

FIG. 9 is a front elevation view of the hanger for a bird feeder of FIG. 8;

FIG. 10 is a rear elevation view of the hanger for a bird feeder of FIG. 8;

FIG. 11 is a left elevation view of the hanger for a bird feeder of FIG. 8;

FIG. 12 is a right elevation view of the hanger for a bird feeder of FIG. 8;

FIG. 13 is a top plan view of the hanger for a bird feeder of FIG. 8; and,

FIG. 14 is a bottom plan view of the hanger for a bird feeder of FIG. 8.

Broken lines and portions contained within broken line are not claimed.
